UNITED STATES PATENT OFFICE.

LE ROY COPLIN, OF WINDBER, PENNSYLVANIA.

AUTOMATIC NONSET STOP FOR TALKING MACHINES.

1,415,800.

Specification of Letters Patent.

Patented May 9, 1922.

Application filed October 11, 1920. Serial No. 416,227.

To all whom it may concern:

Be it known that I, LE ROY COPLIN, a citizen of the United States, residing at Windber, in the county of Somerset and 5 State of Pennsylvania, have invented certain new and useful Improvements in Automatic Nonset Stops for Talking Machines, of which the following is a specification.

This invention relates to stop mechanism 10 for talking machines to automatically stop the machine when the record is finished.

The object of the invention is to provide an automatic non-set stop for talking machines controlled exclusively by the motion 15 of the tone arm and which requires no setting or attention by the operator.

Another object is to so construct such mechanism that the brake will be applied gently and smoothly to stop the turntable 20 avoiding abrupt stoppage of the machine and the injurious effects incident thereto.

Another object is to provide a stop of this character which can be used on any talking machine not employing a gear driven tone 25 arm such as the Edison, without in any way altering the machine; which is simple in construction and cheaply manufactured and which operates simply and positively.

Another object is to provide a break applying device for talking machines so constructed and connected with the tone arm that the break can only be applied when the tone arm ceases to move which occurs when 30 the last thread of the record is reached.

Another object is to so construct and connect such a stop that the tone arm may be lifted and moved out beyond the turntable to provide for the change of a record without releasing the brake, which release 35 is effected by the moving inward of the tone arm into playing position on the record.

With these and other objects in view, the invention consists in certain novel features of construction as hereinafter shown and 40 described and specifically pointed out in the claims, and in the drawings illustrative of the preferred embodiment of the invention.

In the accompanying drawing:

Figure 1 represents a top plan view of a talking machine turntable with the tone arm shown in operative position relatively thereto, a part of said table being broken out to disclose the attachment constituting this invention, the parts of the attachment being

in the position assumed when the record is playing.

Fig. 2 is a similar view with the parts in the position assumed at the completion of the record just prior to the application of 60 the brake.

Fig. 3 is a central transverse section taken on the line 3—3 of Fig. 2.

Fig. 4 is a detail transverse section taken on the line 4—4 of Fig. 1. 65

Fig. 5 is a detail perspective view of the brake, and,

Fig. 6 is a detail sectional view taken on the line 6—6 of Fig. 1.

In the embodiment illustrated a turntable 70 T is shown mounted centrally on a post P and over which is mounted to operate a tone arm A carrying the reproducer R. These parts are of ordinary construction such as are usually found in talking machines employing disc records and form no part of the invention. 75

The attachment constituting the invention is mounted beneath the turntable T preferably on a metal plate to be screwed on the 80 board underneath the turntable, and comprises a gear 1 mounted on the center post P and which meshes with a larger gear 2 carrying on its upper face a friction washer 3 which is here shown in the form of a three 85 pointed star, one point of which carries at its outer end an upstanding pin or stud 4 for a purpose presently to be described.

A plate 5 is mounted loosely at one end on a screw bearing 6 which is here shown in 90 radial alinement with post P. This plate 5 has an upwardly offset intermediate portion 8 to permit the large gear 2 to operate thereunder as is shown clearly in Fig. 3. The free end of this plate 5 projects beyond the 95 perimeter of the turntable T and is equipped with an operating knob 7, which may be used to manually release the brakes when it is not desired to lift the tone arm but it is not necessary to the operation of the attachment. 100 The plate 5 is also provided on its inner edge with a laterally extending arm 9 having at its terminal a downturned lip 10 for a purpose presently to be described. This plate 5 also has extending from its opposed side 105 edges in advance of the offset portion 8 arms 11 and 12 provided with longitudinally extending arcuate slots 13 through which pass headed studs 14, these studs and slots operating to limit the swinging movement of plate 110

5 in opposite directions, which movement is accomplished by means presently to be described.

A connecting bar or pitman 15 is pivoted 5 at one end to the inner end of the offset portion 8 of plate 5 and has a pin and slot connection at its other end with a link 16. This link 16 is pivoted to one arm 17 of an L-shaped bracket, the arm 18 of which is secured by riveting or otherwise to the tone arm A as is shown clearly in Fig. 6. The pivot which connects link 16 with arm 17 has a coiled spring mounted thereon between said members and provides a friction joint, the 15 object of which will be hereinafter set forth. The pin and slot connection between bar 15 and link 16 provides for the unsteady motion of the tone arm while playing a record without affecting the stopping mechanism.

20 A brake 20 is carried by one end of an L-shaped lever 21 fulcrumed at its other end to the machine as shown at 22 and to the elbow of which is pivotally connected one end of a bar 23 as shown at 24. The brake 20 is positioned adjacent the perimeter of the turntable T and is movable toward and away from the edge of said table on the application or release of the brake. The other end of the bar 23 carries a longitudinally slotted 25 head 25 through the slot 26 of which passes a headed stud 27 carried by an arm 28 of plate 5. The terminal of head 25 has a depending lug 29 extended over the edge of arm 28 at one side thereof and is designed 30 to be positioned in the path of the stud 4 carried by the friction washer 3 on gear 2, the slot 26 in the head 25 permitting the brake bar 23 to be moved longitudinally for applying and releasing the brake, the application of the brake being effected by the engagement of the pin 4 with the lug 29 on said head and which occurs only when the tone arm ceases its movement.

The arms 9 and 28 of the plate 5 are spaced 45 apart and the stud 4 carried by the washer 3 engages both the lug 29 and the lip 10 in a manner to be described.

A coiled spring 30 is connected at one end with the lower face of bar 23 and at its other 50 end with the supporting frame of the machine and operates to normally move the bar outward to hold the brake 20 in inoperative position and to return it to this position when released and the machine is in operation.

55 In the use of this attachment, the parts are mounted as shown, and the brake applied and locked by the engagement of pin 4 with lug 29 on the brake bar which is accomplished by the stoppage of the tone arm 60 at its extreme inward or center position, which position is reached on the completion of a record. Then to change a record or to repeat the one which has been played, the reproducer R is lifted and moved outward 65 beyond the perimeter of the turntable and the

record mounted thereon, which movement owing to the friction joint between links 16 and 17 permits said tone arm to be so moved without releasing the pin from the lug 29, so that the brake remains applied. After 70 change the record or if the one already on the machine is to be repeated, the reproducer R is moved inward which movement, owing to the fact that links 16 and 17 are in longitudinal alinement and are so held 75 in the friction joint 19, operates to exert a pulling action on the rod 15 and thereby move plate 5 rearward a sufficient distance to disengage lug 29 from pin 4 whereby the brake is automatically released and when the 80 needle engages a groove in the record, which is rotating the tone arm is guided inward or centerward in the usual manner. The knob 7 mounted on the free end of the plate 5 is designed to start the record without 85 moving the tone arm should the reproducer rest on the record with the brake applied. When this knob is used it is grasped by the operator and the plate is moved rearward to release lug 29 from pin 4, and permits the 90 brake bar to move outwardly under tension of spring 30 and to release the turntable. Five turns of the record will move the tone arm five threads nearer to the center of the record and during this movement the gear 2 95 will make one revolution. The revolution of the gear 2 correspondingly rotates the friction washer 3 and on each revolution thereof the stud 4 engages the lip 10 of plate 5 which lip is bent at an angle and to pull the plate 100 forward in the position shown in Fig. 1, the impelling force of the tone arm operates to move the plate 5 including the lip 10, rearward to the position shown in Fig. 2. The pin or stud 4 operates when it engages lip 10 105 to draw down the plate forward to the limit of the slots 13, thus slipping friction joint 19. It will thus be seen that the tone arm will swing the plate 5 rearwardly while the pin 4 engaging the lip 10 will swing it 110 forwardly. The backward movement produced by the action of the tone arm on the plate 5 causes the pin 4 to escape engagement with the lug 29 on the brake bar 23 thereby avoiding the application of the brake 115 during the playing of a record, it being necessary to provide this oscillatory movement of plate 5 so that when the tone arm reaches the last line of the record the movement of said arm will stop and consequently it will 120 have no effect on plate 5 so that the lug 29 will be positioned in the path of the stud 4 and will be engaged by said stud on the turning of the gear 2 which will cause the brake bar 23 to be moved longitudinally inward thereby applying the brake and stopping the machine. The friction washer 3 which carries the stud 4 will permit the brake to be applied gently and smoothly and avoid abrupt stoppage of the machine. 125 130

From the above description it will be obvious that if the reproducer is removed from the record by the operator either before or after the record is played the turntable will stop without any attention from the operator. It is impossible for the turntable to run at any time except when the tone arm is being moved centerward.

The preferred embodiment of the invention is disclosed in the drawings and set forth in the specification, but it will be understood that any modifications within the scope of the claimed invention may be made in the construction without departing from the principle of the invention or sacrificing any of its advantages.

What is claimed is:

1. In an automatic non-set stop for talking machines, the combination with a tone arm; of a brake, a spring to hold said brake in inoperative position, means to move said brake against the tension of its spring to apply the brake, and means controlled by the tone arm to move the brake out of the path of said brake moving means while the tone arm is in motion.

2. In an automatic non-set stop for talking machines, the combination with a tone arm; of a brake carrying bar, a spring to hold said bar with the brake normally in inoperative position, rotary means to engage said bar and move it against the tension of its spring to apply the brake, and means controlled by the tone arm to move the bar out of the path of said rotary means while the tone arm is in motion.

3. In an automatic non-set stop for talking machines, the combination with a tone arm; of a brake carrying bar, a spring to hold said bar with the brake normally in inoperative position, rotary means having a stud to engage said bar and move it against the tension of its spring to apply the brake, and means controlled by the tone arm to move the bar out of the path of said stud while the arm is in motion.

4. In a stop of the class described the combination with a tone arm; a turntable, a post connected to rotate said table, a reciprocating brake carrying bar, a spring to hold said bar with the brake normally in inoperative position, rotary means operable by the turntable operating means to engage said bar and move it against the tension of its spring to apply the brake, and means controlled by the tone arm to move the bar out of the path of said rotary means while the tone arm is in motion.

5. The combination with a tone arm and a turntable and its operating post; a reciprocating brake carrying bar, a spring to hold said bar with the brake normally in inoperative position, a gear fixed to rotate with said post, another gear meshing with said post carried gear, a friction disk carried by

said second mentioned gear and having a projection to engage said bar to move it against the tension of its spring to apply the brake, and means controlled by the tone arm to move the bar out of the path of said disk while the arm is in motion.

6. The combination with a tone arm and a turntable; of a reciprocating brake carrying bar, a spring to hold said bar with the brake normally in inoperative position, a plate pivoted to swing horizontally under said turntable, a connection between said plate and bar whereby the bar swings with the plate, a connection between said plate and tone arm whereby the plate is swung in one direction by the tone arm, rotary means to engage said plate and move it in a direction opposite to that in which it is moved by said arm whereby said bar is positioned in the path of said rotary means, the arm moving said bar out of said path while the arm is in motion.

7. The combination with a tone arm and a turntable; of a brake for said turntable, an operating bar connected with said brake, a plate pivoted to swing horizontally under said turntable, a connection between said plate and bar whereby the bar is moved with the plate, a cam member carried by said plate, a rotary element mounted to engage said cam member and move said plate in one direction whereby the brake bar is positioned in the path of said element, and a connection between said plate and tone arm whereby the plate is swung away from said rotary element a sufficient distance to prevent the engagement of the bar by said element while the tone arm is in operation.

8. The combination with a tone arm and a turntable; of a brake for said turntable, a bar connected to operate said brake, a plate mounted to swing horizontally under said turntable, a pin and slot connection between said plate and bar to provide for the swinging of the bar with the plate and permit the bar to slide longitudinally on the plate, means for limiting the swinging movement of said plate, a rotary element mounted to engage said plate and swing it in one direction to bring the brake bar in the path of said element, and a connection between said plate and tone arm whereby the brake bar is moved out of the path of said element during the operation of the tone arm.

9. The combination with a tone arm and a turntable; of a brake for said turntable, a bar connected to operate said brake, a plate mounted to swing horizontally under said turntable, a pin and slot connection between said plate and bar to provide for the swinging of the bar with the plate and permit the bar to slide longitudinally on the plate, means for limiting the swinging movement of said plate, a rotary element mounted to engage said plate and swing it in one direc-

tion to bring the brake bar in the path of said element, a pitman pivoted at one end to said plate, a bracket carried by said tone arm, and a link connecting the other end of said pitman with said bracket, the joint between the bracket and the link being in the form of a friction joint.

10. In an automatic non-set stop for talking machines, the combination with a tone arm, of a brake, a spring to hold said brake in inoperative position, means to move said brake against the tension of its spring to apply the brake, means controlled by the tone arm to move the bar out of the path of said 15 brake moving means while the tone arm is in motion, and means to permit unsteady motion of the arm while playing without affecting the braking mechanism.

11. In an automatic non-set stop for talking machines, the combination with a tone arm; of a brake carrying bar normally held in inoperative position, rotary means having a stud to engage said bar and move it to apply the brake, a member mounted for oscillatory movement and having a pin and slot connection with said brake bar whereby said bar is moved out of the path of said stud by the swinging of said member in one direction, a projection carried by said member in the path of said stud to be engaged by the stud on each revolution of said rotary means to swing said member to position the brake bar in the path of the stud, and means operable by the inward movement of the

tone arm to move said member in the opposite direction and thereby move the brake from the path of the stud before its engagement thereby.

12. In an automatic non-set stop for talking machines, the combination with a tone arm; of a brake carrying bar normally held in inoperative position, rotary means having a stud, a member mounted for oscillatory movement, said brake bar and member having projections mounted for successive engagement by said stud, the engagement of the stud with the projection of said member operating to position the projection on the brake bar in the path of the stud, and means operable by the inward movement of the tone arm to move said brake carried projection out of the path of the stud before its engagement thereby.

13. In an automatic non-set stop for talking machines, the combination with a tone arm; of an arm carried by said tone arm, a bar pivoted at one end to the free end of said arm, a brake normally held in inoperative position, means to apply said brake, and cooperating means carried by said bar and one member of said brake applying means, operable on the inward movement of the tone arm to prevent application of the brake.

In testimony whereof, I affix my signature hereto.

LE ROY COPLIN.
